United States Patent Office.

JAMES S. CASEY, OF VOLUNTOWN, CONNECTICUT.

Letters Patent No. 95,767, dated October 12, 1869.

IMPROVEMENT IN STOP-MOTION FOR DRAWING-FRAMES.

The Schedule referred to in these Letters Patent and making part of the same.

To all whom it may concern:

Be it known that I, JAMES S. CASEY, of Voluntown, in the county of Windham, and State of Connecticut, have invented a new and valuable Improvement in Governors and Stop-Motion for Railway-Heads; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of my invention in elevation.

Figure 2 is a plan view of same.

My invention relates to spinning-machines; and consists mainly in the construction and novel arrangement of devices, whereby an evenness of roving is insured, and all breakage or other accidents to material or machinery, caused by bunches or lank places in the roving, prevented. It is a simple and efficient stop-motion, easily applied.

The letter A, of the drawings, represents the top drawing-roll, the shaft of which is lengthened, and has secured to its end a small spur-wheel, a'.

B and C designate eccentrics revolving about the pins b and c, respectively. These eccentrics are toothed for about three-quarters of their circumference, and so weighted as to automatically present the lank and smooth side of each to the small spur-wheel on the end of the top roll.

The axis or pins b and c are fixed in the ends of the yielding-jaws d' d, hinged at d' d to the forked support D.

The eccentrics B and C are drawn toward each other by the spiral spring E attached to the jaws d, d', by the screw-bolts and nuts e e, and their distance apart regulated by means of the set-screws f f in the forked ends of support D.

The support D is adjusted, so that the eccentrics shall gear with the spur-wheel a', by means of its slotted arm D', in connection with the sliding standard G, working in its slotted support F, the whole being arranged so as to bring the eccentrics B and C to any desired position.

The support D is provided with a fork, H, pivoted at h, whose fingers, adjustable in slotted supports by means of the set-screws h' h', engage with the pins b' and c', fixed at suitable points in the faces of the eccentrics B and C.

Fixed in the opposite end of the fork H is a small prismatic rod, i, which engages in a small notch in the rod I.

The upper end of the rod I is formed into a handle or knob. Its lower end is keyed on the horizontal rod K.

This rod or shaft K turns in its bearings k k', and has a spiral spring, k, coiled around it, one end of which is fixed to it by the clamp l, the other end being firmly fixed to the bearing k'.

The end of the rod K, which extends beyond the bearing k', has two notches or depressions, one extend-

ing beyond the other in such a manner as to release the catch of the shipper when the rod K is turned by the action of the spiral spring k.

The yielding or up-and-down motion of the top roll is placed under perfect command by means of the weights m m and coiled springs s s, producing the necessary tension for properly condensing the roving.

The operation of my invention is as follows:

The evener being set to produce the required size or number of roving, the eccentrics B and C of my stop-motion are also set, to bring the lank and smooth portions of their circumference within a thirty-second part of an inch of the spur-wheel a' on the end of the top-roll, which plays between them, and the stop-motion is ready for operation.

Now, should the roving break or run down fine from the cards giving out, or other causes, making it impossible for the evener to keep up the number of roving, the small spur-wheel a' will drop, and engage with the lower eccentric C, whose pin c' will engage with the lower tine of the fork H, raising it, and thereby depressing the small catch i out of the notch in the upper part of the rod I.

The rod I being released, the shaft K, operated by the spiral spring k, turns one-quarter round, thereby operating the belt-shifter to stop the machine.

In case bunches run through, or the rolls wind up, the small spur-wheel a' is forced to rise, and engage with the upper eccentric B, whose pin b' raises the upper tine of the balanced fork H, and the belt-shifter is caused to throw off in the same manner as before described.

It will be perceived that my stop-motion is not liable to much wear, as it is still, except when called on to perform its duty.

What I claim as my invention, and desire to secure by Letters Patent, is—

1. In combination with the eccentrics B and C, or their equivalents, the spur-wheel a', secured to the extended shaft of the top roll A, substantially as shown and described.

2. The eccentrics B and C, partially toothed and weighted, so as to present their smooth and lank sides automatically to the geared end of the top roll, substantially as specified.

3. In combination with the eccentrics B and C, the fork H, constructed and arranged to operate substantially as specified.

4. The stop-motion herein described, having sliding standard G, adjustable support D, with hinged and adjustable jaws d d', eccentrics B C, balanced fork H, spur-wheel a', shaft K, and spiral spring k, all constructed and arranged to operate with the belt-shifter, substantially as specified.

In testimony that I claim the above, I have hereunto subcribed my name, in the presence of two witnesses.

Witnesses:
